UNITED STATES PATENT OFFICE

KARL HUNCIKER, OF CHICAGO, ILLINOIS, ASSIGNOR TO IRA E. McCABE, OF CHICAGO, ILLINOIS

MANUFACTURE OF ELECTRIC MERCURY BULB SWITCHES

Application filed September 18, 1929. Serial No. 393,389.

This invention relates to improvements in the manufacture of electric mercury bulb switches and more particularly to the method and automatic apparatus for producing the 5 mercury bulb switches in which the electrodes and a filling stem are inserted in the open end of a glass bulb, the sides brought together to seal the electrodes and filling stem and support the electrodes in proper 10 positions in one operation, whereby the bulb switch is prepared for the insertion of the mercury or other electrical conducting fluid, the exhausting of the air, and substitution of the gas to reduce arcing are accomplished 15 through the filling stem which is then tipped off.

It is an object of this invention to provide an automatic apparatus which through successive steps produces the bulb switch ready 20 for the reception of the conducting fluid and gas in a prompt and uniform manner and in addition thereto shapes the bulb adjacent the sealed end, at the same time, to insure that the electrodes projecting into the interior 25 of the bulb are not contacted by the wall of the bulb.

While it is old in the manufacture of electric light bulbs to produce pinch seals and provide filling stems, the accuracy in locating 30 the electrodes is not so vital as in mercury tube or bulb switches and, while the filling stem is ordinarily, in this art mentioned, provided at the end opposite the seal, the stem has not been employed for shaping the bulb 35 before and after the sealing process.

The method and apparatus disclosed herein produces a uniform product automatically at much less expense than heretofore, inasmuch as the machine accomplishes the result with 40 out manual operation thereby avoiding the variations naturally resulting between the products of individual manual operators.

With these and other objects in view, reference is made to the accompanying sheets of 45 drawings which illustrate preferred forms of this invention, with the understanding that minor detail changes may be made without departing from the scope thereof.

In the drawings:

50 Figure 1 is a fragmentary top plan view

illustrating the essential elements of the apparatus to carry out the steps of this invention.

Figure 2 is a fragmentary plan view of the end of a filling stem. 55

Figures 3 and 4 are detail plan views of the respective leading in wires and electrodes employed in one type bulb switch.

Figure 5 is a detail plan view of the open ended bulb before it is sealed. 60

Figures 6 and 7 are views in end and side elevations, respectively of a sealed bulb switch of the type employing the leading in wires and electrodes illustrated in Figures 3 and 4.

Figures 8 and 9 are similar views of another type of bulb switch employing a pair of leading in wires and electrodes similar to Figure 3 and a modified form of electrode secured to a pair of leading in wires. 65

Figure 10 is an enlarged detail view in 70 side elevation, with parts broken away, of a work holder supporting an open end bulb, electrodes and filling stem with the compressing jaws open before the opened end of the bulb is sealed. 75

Figure 11 is a view similar to Figure 10 showing the jaws completing the seal and the air block and inclined track as supported below the table.

Figure 12 is a view similar to Figure 11 80 with the jaws opened after completing the seal of the open end of the bulb showing the second air block as supported below the table.

Figure 13 is an enlarged fragmentary view 85 partly in central vertical section and partly in side elevation of the filling stem core rod and reciprocating means therefor.

Figure 14 is a fragmentary view in side elevation showing the arrangement of jaws to form the type bulb switch shown in Figures 8 and 9. 90

The apparatus for carrying out this invention, as illustrated upon the drawings, includes a rotatable table or turret 1, preferably circular in shape, having a plurality 95 of equally spaced upwardly extending work holder bosses 2 also arranged equi-distant from the center of rotation. This table or turret 1 is provided with a step by step rotating mechanism of which there are sev- 100

eral types upon the market and as this mechanism is not a part of this invention it is not necessary to illustrate or further describe such a well known mechanism.

- 5 Each boss 2 is provided with a central vertical bore for rotatably mounting a vertical work support referred to in its entirety by the reference numeral 3 upon Figure 1 of the drawings. The work holders 3 are brought at 10 preferably four successive stops of the table or turret 1 between the horizontal flames of oppositely disposed gas jets 4 which are supported in the same plane above the top of the rotatable support 1 in any desired manner 15 and connected to a source of gas supply. Gas jets of this character being well known in the glass manipulation art it is thought they need no further illustration nor description only to state that, as shown, upon 20 rotation of the table 1 in the direction of the arrow, the flames of the first three jets are increased successively in intensity and the fourth diminished preferably below the intensity of the first jet in the series.
- 25 This apparatus is designed to produce mercury bulb electric switches of the type shown in Figures 2 to 9, inclusive. Each bulb switch, as shown in Figures 2, 3, 4 and 5, includes a hollow glass tube 5 which forms 30 a filling stem, to be hereinafter described; a leading in wire 6 welded to an electrode 7 which is bent near its extremity at right angles to its main body and which is preferably sheathed within a short glass tube 8, 35 as shown; a leading in wire 9 welded to a forked electrode 10 which embraces and supports a cup 11 of insulating material at an angle to the main body with the tines of the fork extending therebeyond preferably in the 40 same plane as the leading in wire 9; and an open ended tubular glass bulb 12. In the form shown in Figures 6 and 7 the side walls of the open end of the tubular glass bulb 12 have been brought together to centrally 45 embrace the filling stem 5 with its open end communicating with the interior of the bulb, with the leading in wires 6 and 9 on opposite sides thereof with the glass sheath 8 imbedded in the closure supporting the angular terminal 50 of the electrode 7 entering the interior of the cup 11 which is supported by the forked electrode 10 from the leading in wire 9 to incline in the direction of the bottom of the opposite closed end of the bulb 12 with 55 the tines of the electrode 10 extending parallel to but separated from the side walls of the bulb. Figures 8 and 9 illustrate another form of this bulb switch in which the leading in wires are arranged in pairs, one 60 pair being similar to leading in wire 6 having the bent electrode 7 within the sheath 8, as above described, and the other pair similar to the leading in wire 9 except the electrode instead of being forked is a continuous loop 65 13 joined at each end to the leading in wires.

In this type the open end of the tubular glass bulb 12 has been folded in upon itself to centrally embrace the filling stem 5 and support the pairs of leading in wires 6 and 9 in parallel planes on each side thereof.

70 The assembled bulb switches, as illustrated in Figures 6 to 9 inclusive, show the filling stems 5 communicating with the interior of the respective bulb 12. After being so produced by this improved apparatus, the assembly is removed and the switch is completed by exhausting the air through stem 5 from the interior of the bulb 12 and replacing it by filling the bulb through the stem with the required amount of mercury and inert gas 80 and then tipping off or sealing the filling stem 5 adjacent the closed end of the bulb 12.

85 This invention not only contemplates supporting the filling stem 5 with the leading in wires 6 and 9 in the relation shown in Figures 7 and 9, and sealing them in that position within the sealed end of the bulb 12 by heating that end to plasticity and compressing it, but also to employ the filling stem 5 to admit air under sufficient pressure just before the compressing operation is completed and immediately thereafter while the compressed end is cooling to maintain the tubular contour of the heated walls immediately adjacent the seal and prevent such heated and semiplastic walls from collapsing, elongating or tapering from the tubular cold portion to the sealed end in order that in the resultant product the electrodes 7 and 10 or 13 with the cup 11 will all be held in the proper places free and out of contact with the side walls of the bulb 12.

90 An apparatus of this general type has been 95 disclosed in our joint application, Serial No. 366,916, filed May 29, 1929, so that this invention applies to the particular manner and times as well as the mechanical construction for admitting the air under pressure to the interior of the heated and cooling bulb 12.

100 The general construction and operation of the apparatus is as follows. Each boss 2 upon the step by step revolving table 1 supports a work holder 3. Each work holder includes a shouldered base 14 having a centrally depending tubular guide 15 adapted to pass through the vertical bore of the boss 2 and mount below the table 1 a pulley or gear wheel 15^a to cooperate with the rotating mechanism of the table to rotate the work holder continuously at each stop of the table during its step by step rotation movement as each work holder halts successively between each successive pairs of gas jets. 115 Since such mechanism is well known in glass manipulating machinery it is not further disclosed nor described herein as it forms no part of this particular invention. It is preferable to provide ball bearings 17^a between 120 110 125 130

the top of the boss 2 and under side of the shoulder of the base 14.

An electrode and filling stem positioning block 16 is supported in axial alignment with the base guide 15, upon a cross head 17 adjustably mounted upon supports 18 extending upward from opposite sides of the center of the base 14. The supports 18 mount above the cross head 17, a releasable bulb clamping and positioning device including a rectangular frame 19 pivoted at its corners, the longer sides provided with central inwardly extending coacting bulb clamping members 20 with the shorter sides centrally pivoted upon the upper extremities of the supports 18. One support is hollow and the pivot upon that support is in the form of a shaft 21 secured at its upper end to one of the shorter members of the clamping and positioning frame 19 and passes through the support and projects below the base 14 and mounts a wing nut 22 held thereon preferably by a set screw, as shown. A resilient member 23 is secured to the base 14 having its free outer end indented and adapted to engage the outer edge of one of the wings of the nut 22 with the indented member 20 in the position assumed when holding a bulb 12 between them. A coil spring 24 secured at one end to the outer end of the outer wing of the nut 22 with the other end engaging the base 14 and exerts sufficient tension against resilient member 23 so that when it is desired to remove the bulb 12 the wing is manually released and the spring 24 causes the frame 19 to open and hold it open until another bulb is inserted and the members 20 caused to engage it by manually rotating the nut 22 until the wing engages the indentation in the resilient holding member 23.

The electrode and filling stem positioning block 16 is removable, is provided with a central bore for positioning a filling stem 5, as shown, and upon the top with oppositely disposed recesses for receiving and positioning the electrode supporting leading in wires 6 and 9 with a positioning pin 25 extending from one side adapted to engage in a notch in the cross head 17 to maintain its position. Before operating the apparatus a plurality of equal length filling stems 5 are placed within reach of the operator also a plurality of blocks 16 which have been filled with the proper electrode supported leading in wires. In starting the operation a filled block 16 is placed upon the cross head 17 and a filling stem 5 inserted within the central base. Another adjustable cross head 26 is mounted upon the supports 18 a sufficient distance below cross head 17 to engage the lower end of the filling stem 5 and support it with its upper end the proper distance above the top of the block 16. Then the bulb clamp 20 on the frame 19 of the bulb positioning device is opened by rotating the wing nut 22 and the

open end of a bulb 12 is placed over the electrodes and filling stem projecting above the top of the block 16 and the wing nut 22 rotated to clamp the bulb 12 and by means of being brought with engagement with the member 23 will hold the bulb in that position until manually released and removed. The mechanism of the apparatus is started and as each empty work holder halts in the step by step rotation of the table 1 it will be supplied by the operator with a filled block 16, filling stem 5 and bulb 12. As the table halts at each step the work holder is continuously rotated. When the work holder halts between the flames of the first pair of gas jets 4, the flames play upon opposite sides of the open end of the bulb 12 and as the work holder continuously rotates the lower walls of the bulb are gradually heated, then the work holder is advanced and halted between the still more intense flames of the second pair of jets, rotated therebetween, and further heated and to a higher degree, then the work holder is advanced and halted between the still more intense flames of the third pair of gas jets, rotated therebetween. At this point the continued application of heat in increasing degrees has brought the lower portion of the walls of the open end of the bulb to a uniform state of plasticity sufficient to be compressed and united to embrace and seal the electrode supporting leading in wires 6 and 9 and the end of the filling stem 5.

The compressing and sealing the open end of the bulb to embrace and support the leading in wires and filling stem is accomplished by a pair of oppositely disposed compressing jaws 27 pivotally mounted within recesses provided therefor in the cross head 17. The jaws are moved about their pivots by links 102 28 pivoted at one end to the respective jaws and at the other to oppositely disposed ears 29 upon a tubular actuating member 30 which is mounted to reciprocate axially within the base 14, tubular guide 15 within the boss 2, and to normally extend below the table 1 when the jaws 27 are in open position, as shown in Figures 10 and 12. As the work holder is moved from between the flames of greatest intensity with the open end of the bulb in a compressible state, the lower end of the actuating member 30 projecting below the rotating table 1, is caused to engage and ride over an inclined track 31, as shown in Figure 11, whereby the jaws are brought together to engage the opposite sides of the open end of the bulb to compress them and then released to assume the normal open position.

At the halt following the compression and sealing of the bulb the work holder is rotated between the less intense flames of the fourth pair of jets, to prevent too rapid cooling, and at the following halt the bulb with the compressed end embracing and sealing the lead-

ing in wires and filling stem approaches the operator and is ready to be removed.

Figures 10, 11 and 12 illustrate one pair of jaws which compress the walls of the bulb to form the type of bulb switch shown in Figures 6 and 7. When it is desired to form the type shown in Figures 8 and 9, two pairs of oppositely disposed jaws are provided of the form shown in Figure 14 with the additional jaws 32 pivotally mounted upon the exterior of the cross head 17 and connected by similar links 28 to the actuating member 30.

The leading in wires 6 and welded electrodes 7 with sheath 8 are articles of standard mass production as well as leading in wires 9 and welded electrodes 10 embracing and supporting cup 11 and likewise leading in wires 9 and welded electrode 13 embracing and supporting cup 11, so that they are all of the same dimensions and similar in construction and when placed in block 16 each set will be similarly supported to the preceding set. The cross head 17 is adjusted so that when the open ended bulbs 12 of different sizes and lengths are engaged by the position frame 19 the electrodes will project into the interior of the bulb the proper distance to be embraced and sealed within the compressed walls of the open end. The filling stems 5 are preferably of uniform length for bulbs of the same size but may be of various lengths for various size bulbs and the cross head 26 is therefore adjustable so that the stem may be always supported with its upper end the proper distance above the block 16.

To prevent the heat and pressure during the compressing action of the jaws upon the heated and semi-plastic walls of the open end of the tube closing the opening through the filling stem, a core 33 is provided in the form of a rod of less diameter than that of the filling stem and is adjustably mounted upon a reciprocating member 34 mounted to slide on a guide 35 carried upon the cross head 26 and within the actuating member 30. The core rod 33 passes through an aperture provided therefor in the cross head 26 and through the filling stem bore in the block 16 and is normally adjusted by the set screw 36 to the reciprocating member 34 to project slightly above the upper end of the filling stem during the heating and compressing of the walls of the open end of the bulb 12. The core rod is caused to reciprocate by means of an operating lever 37 pivoted at one end to an adjustable collar 38 secured about one of the supports 18. The free end passes beyond the other support 18 and is connected to the base 14 by a coil spring 39 which normally draws the free end downward in the direction of the base. The operating lever 37 is connected to the reciprocating member 34 by a pivoted link 40. On the outer surface of

the lever 37 a flat spring 41 is secured at one end and two pins 42 and 43 secured adjacent the free end which pass through apertures therefor in the lever 37. The pin 42 is positioned to normally enter a vertical groove in a detaching block 44 carried on the adjacent jaw operating link 28 and the pin 43 is arranged to be adapted to engage within a horizontal groove 45 upon the adjacent support 18 and hold the free end of the lever in its uppermost position, when manually lifted, against the tension of the spring 39 when the jaws 27 are open and thereby support the core end in proper relation to the top of the block 16 through the link 40 and reciprocating member 34, as shown in Figure 10. The groove in the detaching block 44 is curved at its lower end to join the outer surface of the block and the block is so positioned upon the link 28 that with the lever held by the pin 43 in its upper position as the link 28 moves upward to close the jaws 27, as shown in Figure 11, the curved lower end of the groove forces the pin 42 outward so that at the end of the closing movement of the jaw the spring 41 withdraws the pin 43 from the groove 45 and releases the lever 37 to be drawn downward by the spring 39 and withdraw the core rod 33 from within the sealed end of the bulb 12, as shown in Figure 12. The core rod 33 remains in this position until the operator removes the sealed bulb 12 and replaces the empty block with one supporting another set of electrodes and inserts another filling stem. The sealed bulb 12 is manually released by one hand of the operator releasing the wing nut 22 and the same hand may be used to thereafter lift the free end of the lever 37 until the pin 43 enters the groove 45 while the other hand is employed in removing the sealed bulb embracing the leading in wires and filling stem.

As the open end of the bulb 12 is rotated between the flames of the first two sets of gas jets its temperature is increased gradually without fracture to such extent that as it rotates between the flames of greatest intensity of the third set of gas jets it becomes sufficiently plastic on leaving this position to be compressed to seal therein the leading in wires 6 and 9 and filling stem 5. While in this semi-plastic or plastic state the weight of the heated glass of the open end will tend to cause the lower walls to approach each other or taper downwardly toward the center and after the sealing action of the jaws 27 and while rotating between the flames of lesser intensity of the fourth set of gas jets this tendency to taper is increased by the weight of the compressed sealed end. To prolong the active life of the bulb switch in use and to prevent cracking, the electrodes as well as the contained cup 11 should be entirely free of the sides of the bulb, and to so maintain them the cylindrical contour of

the bulb should be maintained adjacent the sealed end, so that it is important to prevent the tapering of the side walls when in a semi-plastic or plastic condition.

5 To accomplish this result, this invention contemplates the admission of air under sufficient pressure into the interior of the bulb just preceding the sealing action of the jaws 27 and during the halt of the sealed bulb between the last set of gas flames. To this end, the reciprocating actuating member 30 is tubular in form as well as the reciprocating member 34 and guide 35 and that portion of the member 34 which is thickened to adjustably engage the lower end of the core rod 33 is perforated so that there is an air passage from the bottom of the actuating member 30 through the aperture in the cross head 26 and, as the core rod is of less diameter than that of the filling stem 5, also through the filling stem. As the work holder assumes its position between the flames of greatest intensity and is halted the open lower end of the actuating member 25 30 wipes over and registers with a stationary block 45 which contains a duct 46 connected to a source of air under the desired pressure, not shown, and is provided with a port 47 adapted to register with the halted open end 30 of the actuating member 30, whereby air under sufficient pressure is admitted into the interior of the bulb 12 during this heating period through the upper end of the filling stem, as shown in full lines in Figures 10 and 35 12 and indicated in dot and dash lines in Figure 11, to maintain the cylindrical form of the open end of the bulb 12. As the work holder advances to the position between the last set of gas flames the jaws 27 complete 40 the seal as shown in Figure 11 and then open as shown in Figure 12.

As the core rod reciprocating lever 37 is released immediately the open end is sealed, the core 33 is withdrawn from the retracted 45 end of the filling stem 5 within the sealed end, as shown in Figure 12, the travel of the core rod 33 is so adjusted that when in this position there is an unobstructed passage 50 from the lower part of the filling stem into the interior of the sealed bulb. As the work holder halts between the last set of gas flames the lower end of the tubular actuating member 30 wipes over a stationary block 48 similar to the block 45, having a duct 49 55 also connected at one end to a source of air under sufficient pressure to pass through a port 50 registering with the open end of the halted actuating member 30 and through said member and through member 34, guide 35, cross head 26 and filling stem 5 and to prevent the walls of the bulb adjacent the sealed end from excessive tapering and maintain the cylindrical form as near to the seal as possible.

65 This invention provides several improve-

ments over the structure disclosed in the said joint invention of Ira E. McCabe and myself. It is particularly distinguished therefrom by the provision of air under pressure at two places during the successive steps in the formation of the bulb switch upon the apparatus. In the apparatus disclosed herein, the open end of the bulb is successively rotated between flames of increasing intensity, and during the halt of the table and the rotation of the work-holder between the flames of greatest intensity, just before the lower walls of the bulb are compressed, the heat is so intense that the walls of the bulb become white hot and would, under normal conditions, transmit such heat to the end of the filling stem which projects into the bulb and cause the filling stem to become semi-plastic, possibly to become deformed, so that, when the jaws compress the walls, the contact of the walls with the semi-plastic filling stem will seal the core rod to the filling stem. To prevent such an occurrence, air under pressure is caused to pass continually through the filling stem into the surrounding open ended bulb which not only cools the interior of the filling stem but also, in passing into the bulb and then out the open end, envelops the exterior of the filling stem and sets up a current of air which carries the intense heat of the walls of the bulb away from the stem, so that after the operation of the jaws the core rod may be readily withdrawn.

In this apparatus, provision is made to continuously rotate each work-holder at each 100 halt in the step by step rotation of the table. In order to admit air through the filling stem at the halts on each side of the compressing operation, each member of the core rod actuating and supporting members is 105 tubular in form and the actuating member is mounted to extend below the table to register during these halts with air ports from which air under pressure will pass through said members and supported filling stem about the 110 core rod.

What I claim is:

1. The method of automatically producing electric liquid contact bulb switches by machinery including a step by step movement 115 in which the first step consists in locating and positioning electrodes with a filling stem containing a removable solid core interposed between the electrodes and positioning and supporting the open end of a bulb thereabout, then through the next succeeding steps pass the open end of the bulb between gas flames playing on oppositely disposed walls thereof and when sufficiently plastic compress the plastic walls about the contained electrodes 120 and filling stem to embed the same and form a sealed closure for the bulb with the electrodes extending within the interior, pass air through the filling stem to prevent its adhering to its core before the compression of the 125 130

plastic walls, and remove the filling stem core to provide an opening into the interior of the sealed bulb, admit air under pressure to the interior of the bulb to maintain its contour and in the next succeeding steps reduce the temperature of the seal, and lastly remove the completed structure from the machine.

2. The method of automatically producing electric liquid contact bulb switches by machinery including a step by step movement in which the first step consists in locating and positioning electrodes with a filling stem containing a removable solid core interposed between the electrodes and positioning and supporting the open end of a bulb thereabout, then through the next succeeding steps pass the open end of the bulb between gas flames playing on oppositely disposed walls thereof and when sufficiently plastic compress between molds the plastic walls about the contained electrodes and filling stem to embed the same and form a sealed closure for the bulb with the electrodes extending within the interior, pass air through the filling stem to prevent its adhering to its core before the compression of the plastic walls, and remove the filling stem core to provide an opening into the interior of the sealed bulb, admit air under pressure to the interior of the bulb to mold the plastic wall above the closure, and in the next succeeding steps reduce the temperature of the seal, and lastly remove the completed structure from the machine.

3. The method of producing electric bulb mercury switches which includes positioning of the open end of the bulb about the electrodes and a filling stem containing a removable solid core supporting thereunder, applying heat to the open end of the bulb until it becomes plastic, passing air through the filling stem during the heating of the wall of the bulb to prevent heat therefrom causing the filling stem adhering to the core therein, compressing the plastic wall to embrace, embed and seal the electrodes and filling stem therein and form a sealed closure, and thereafter removing the core while the bulb is still plastic and blowing through the sealing stem and thereby shaping the bulb.

50 KARL HUNCIKER.
